UNITED STATES PATENT OFFICE.

GENE D. CHENETTE, OF AMES, IOWA.

WRENCH.

1,369,784.

Specification of Letters Patent. Patented Mar. 1, 1921.

Application filed March 8, 1920. Serial No. 363,923.

To all whom it may concern:

Be it known that I, GENE D. CHENETTE, a citizen of the United States of America, and resident of Ames, Story county, Iowa, have 5 invented a new and useful Improvement in Wrenches, of which the following is a specification.

The object of this invention is to provide improved means for operating a sliding jaw 10 relative to a fixed jaw in a wrench.

A further object of this invention is to provide improved means for locking a sliding jaw relative to a fixed jaw in a wrench.

A further object of this invention is to 15 provide improved means for operating a sliding jaw relative to a fixed jaw in a wrench in which the sliding jaw moves in a plane transversely of the handle.

My invention consists in the construction, 20 arrangement and combination of elements hereinafter set forth, pointed out in my claims and illustrated by the accompanying drawing, in which—

Figure 1 is a side view and Fig. 2 a view 25 at right angles thereto of a monkey wrench embodying my improvements. Fig. 3 is a cross section on the indicated line 3—3 of Fig. 1. Fig. 4 is a cross section like unto Fig. 3 and showing a modified form of lock. Fig. 5 is a detail view similar to 30 part of Fig. 2, showing a modified form of lock. Fig. 6 is an end elevation of the jaw-operating means. Figs. 7, 8, 9, 10, 11, 12, 13 and 14 are detail views of different 35 forms of manually actuated devices employed to move the jaw-operating means.

In the construction of the device as illustrated in Figs. 1 to 14 inclusive, the numeral 20 designates a stem having a jaw 21 fixed 40 to and extending transversely thereof at one end, the inner face of said jaw preferably being at right angles to the plane of the stem. A portion of the stem adjacent to the jaw 21 is rectangular in cross section and 45 a jaw 22, having angular integral straps or keepers 23, is slidably mounted thereon and is formed with a threaded bore lying in a plane parallel with the stem. The remainder of the stem is formed as a rod, circular 50 in cross section and threaded at its outer end. A ferrule 24 is slidably mounted on the rod portion of the stem and abuts the rectangular portion thereof and also projects laterally therefrom and is formed with 55 a hole registering with the threaded bore of

the sliding jaw. A handle 25, preferably made of wood, is slidably mounted on the rod portion of the stem, is received at one end in the outer end portion of the ferrule 24 and also extends laterally from said stem 60 and is formed with a bore registering with the lateral hole in the ferrule and the threaded bore of the sliding jaw. A bar-washer 26 is mounted at one end on the outer end portion of the rod portion of the 65 stem 20 and a nut 27 is screwed on said rod portion and binds the ferrule 24, handle 25 and bar-washer firmly together. A shaft 28 is journaled in the lateral hole of the ferrule 24 and in the other hole of the bar-washer 70 26 and extends loosely through the lateral bore of the handle 25 as shown by dotted lines in Fig. 1. The shaft 28 is formed with a screw 29 on its inner end meshing with the screw of the threaded bore in the sliding jaw 75 22. A ratchet wheel 30 is mounted rigidly on the shaft 28 adjacent the outer end of the screw 29 and said ratchet wheel extends loosely and freely within a notch 31 in the 80 rectangular portion of the stem. A spider wheel 32 is mounted rigidly on the outer end portion of the shaft 28 and a bushing 33 is interposed between said spider wheel and the bar-washer 26 for the purpose of spacing said spider wheel from said bar 85 washer into a plane parallel with that occupied by the nut 27. A bell-crank dog 34 is fulcrumed on the ferrule 24 and one end portion thereof is adapted, at times, to engage with the ratchet wheel 30 90 while the other end portion thereof extends across the back of the stem 20 adjacent to the inner end portion of said ferrule and in spaced relation to said back. A leaf-spring 35 is mounted on the back of the stem 20 95 and is interposed between said back and the laterally-extending arm of the dog 34. It is the function of the spring 35 to hold the dog in engagement with the ratchet wheel 30; and a latch 36 is pivoted at one end on the ferrule 24 and is adapted to be moved through an arc over and depress the laterally-extending arm of the dog 34 at times, against the spring pressure, to release engagement of said dog with said ratchet 100 wheel. The latch 36 is formed with a flange 37 adapted to be engaged by a digit of the operator for the purpose of moving said latch on its pivot.

In practical use, the sliding jaw 22 may 110

be moved in either direction relative to the fixed jaw 21 by manual rotation of the spider wheel 32 when the dog 34 is released from the ratchet wheel 30. After the jaws 21, 22 are engaged with an object to be held or turned by the wrench, the sliding jaw may be set in such position by engagement of the dog 34 with the ratchet wheel 30, by release of the latch 36 from said dog. Thereafter the wrench may be manipulated with assurance that the jaws will maintain the desired hold upon the object. The spider wheel 32 provides convenient means for operation of the shaft 28 and has increased leverage relative to the milled wheel ordinarily employed in monkey wrenches. The handle 25 incloses adjacent portions of the stem 20 and shaft 28 and provides convenient means for grasping and manipulating the wrench.

In Fig. 4 the bell-crank dog 34, leaf-spring 35 and latch 36 are omitted and a chambered block 38 is mounted on one side of the stem 20. A dog 39 formed with a lateral head 40 is mounted for rotation and reciprocation in the chambered block 38 and is held therein in the direction of engagement with the ratchet wheel 30. The outer end portion of the block 38 is inclined and is adapted to be engaged by the head 40. When it is desired to release the dog 39 from engagement with the ratchet wheel 30, the head 40 is turned manually and, riding on the inclined end of the block 38, said head moves outwardly and withdraws the dog from the wheel against the spring pressure, said head being placed in a position transversely with the back of the stem 20 where it remains until manually removed. In Fig. 5 a latch 41 is substituted for the latch 36 and is slidingly mounted on the back of the ferrule 24 by means of screws 42 seated in said ferrule and extending through a longitudinal slot 45 in the latch. The latch 41 is formed with an outstanding lug 44 on one end adapted for manipulation of the latch and the opposite end portion of said latch is adapted to engage with, depress and hold the lateral arm of the dog 34 at times for the purpose of releasing said dog from engagement with the ratchet wheel 30.

In Figs. 7 and 10 the spider wheel 32 is omitted and the shaft 28 is formed with a lateral hole in its outer end portion. An operating pin or handle 46 is mounted rigidly in, and extends transversely at both ends from the hole in the shaft 28, thus providing convenient means for manipulation of said shaft.

In Figs. 8 and 11 a pin or handle 47 is substituted for the pin or handle 46, is loosely mounted in the hole in the shaft 28 and is formed with a ball 48 on each end to prevent accidental removal of the pin from the hole. This device provides convenient means for

manipulation of the shaft 28 and is susceptible of an adjustment of leverage through extension of the pin 47 relative to the shaft in either direction.

In Figs. 9 and 12 a hexagonal nut 49 is substituted for the operative devices and may be formed on or rigidly secured to the outer end portion of the shaft 28 and have no movement independent of said shaft. It is the function of the nut or bolt-head 49 to be manipulated or operated by another wrench or pliers for the purpose of rotating the shaft 28 in either direction.

In Figs. 13, 14 a further construction is illustrated adapted to be substituted for the devices previously described for rotation of the shaft 28. In this instance bar-washers 50, 51 are mounted on and extend laterally from the outer end portion of the shaft 28 and are secured thereto by a rivet 52 extending through holes in their inner ends and through the pin-hole in the shaft. A lever handle 53, formed with a head having a flat end and three flat faces, is mounted with the head extending between the outer end portions, of the bar washers 50, 51 and secured thereto by a pivot 54. A leaf spring 55 is mounted on the shaft 28 and extends between said shaft and the head of the lever-handle 53 in the space between the bar-washers. It is the function of the leaf-spring 55 to engage the flat end of the head of the lever-handle 53 and hold said handle in extended position as shown by solid lines in Figs. 13, 14, or, to engage one flat face of said handle and hold the same in folded position as shown by dotted lines in Fig. 13. When the handle 53 is in extended position, it provides convenient means for rotating the shaft 28 in either direction.

I claim as my invention—

1. In a wrench having a stem, a jaw fixed to said stem and an opposing jaw slidingly mounted on said stem, the combination with said sliding jaw of a shaft journaled on, extending beyond the outer end of and arranged parallel with said stem, a screw on said shaft acting on said sliding jaw and manually actuated means mounted on the outer end of said shaft and adapted to rotate the shaft and screw thereon, together with a ratchet wheel on said shaft and a spring-pressed bell-crank dog fulcrumed on an axis parallel with and carried by the stem and adapted to engage said ratchet wheel.

2. In a wrench having a stem, a jaw fixed to said stem and an opposing jaw slidingly mounted on said stem, the combination with said sliding jaw of a shaft journaled on and arranged parallel with said stem, a screw on said shaft acting on said sliding jaw and manually actuated means mounted on the outer end of said shaft and adapted to rotate the shaft and screw, together with a ratchet wheel on said shaft, a dog carried by the

stem and adapted to engage said ratchet wheel and a latch carried by the stem and adapted to engage said dog at times.

3. A wrench comprising a stem, a jaw 5 fixed thereto, an opposing jaw slidingly mounted on said stem and formed with a threaded bore, a ferrule mounted on said stem and projecting laterally therefrom, a handle mounted on said stem, projecting laterally therefrom and engaging the ferrule at one end, a washer mounted on said stem and projecting laterally therefrom and engaging the opposite end of said handle, means for securing the stem, ferrule, handle 10 and washer together, the laterally-projecting portions of the ferrule, handle and washer being formed with registering openings, a shaft mounted for rotation in said registering openings, a screw on said shaft 15 engaging said threaded bore, means for rotating said shaft, a ratchet wheel mounted on said shaft adjacent to said ferrule, a dog pivoted on said ferrule and adapted to engage said ratchet wheel at times, and a latch 20 mounted on said ferrule and adapted to engage said dog at times.

4. In a monkey wrench having a stem, a jaw slidingly mounted on said stem, a ferrule on the stem and a screw journaled in 25 the ferrule and acting on the sliding jaw, the combination with said screw of a ratchet wheel mounted rigidly thereon, a bell-crank dog fulcrumed on the ferrule, one arm of the dog being adapted to engage said ratchet 30 wheel, the other arm of the dog extending across the stem, and a latch mounted on the ferrule and adapted to engage and hold the dog out of engagement with the ratchet 35 wheel.

5. In a monkey wrench having a stem, a jaw slidingly mounted on said stem, a ferrule on the stem and a screw journaled on the ferrule and acting on the sliding jaw, the combination with said screw of a ratchet wheel mounted rigidly thereon, a bell-crank 45 dog fulcrumed on the ferrule, one arm of the dog being adapted to engage said ratchet wheel, the other arm of the dog extending across the stem, a leaf spring mounted on the stem and extending between said stem 50 and the latter arm of the dog, said spring being adapted to hold said dog in engagement with said ratchet wheel, and a latch mounted on the ferrule and adapted to engage and hold the dog out of engagement 55 with the ratchet wheel against the pressure of said spring.

6. In a monkey wrench having a stem and a fixed jaw thereon, a jaw slidingly mounted on said stem, a ferrule, handle, washer and 60 nut on the stem and a screw journaled on the ferrule and acting on the sliding jaw, the combination with said screw of a ratchet wheel mounted rigidly thereon, a bell-crank dog fulcrumed on the ferrule on an axis 65 parallel with the stem, one arm of the dog being adapted to engage said ratchet wheel, the other arm of the dog extending across the stem, a spring engaging the dog and adapted to hold it in engagement with said 70 ratchet wheel, and a latch mounted on the ferrule and adapted to engage and hold the dog out of engagement with the ratchet wheel against the pressure of said spring.

Signed at Des Moines, in the county of 75 Polk and State of Iowa, this 28th day of February, 1920.

GENE D. CHENETTE.
